OF BIRMINGHAM, ALABAMA.

COLD-STORAGE STRUCTURE.

1,379,269.

Specification of Letters Patent. Patented May 24, 1921.

Application filed August 13, 1917. Serial No. 185,965.

To all whom it may concern:

Be it known that I, ANDREW C. LEGG, a citizen of the United States of America, residing at Birmingham, in the county of Jefferson and State of Alabama, have invented certain new and useful Improvements in Cold-Storage Structures, of which the following is a specification.

My invention relates to the construction 10 of a cold storage plant, and my object is to so control the circulation of cold air as to prevent the radiation of heat into the storage chamber to any appreciable extent and to keep the air in the cold storage chamber 15 dry and at a uniform temperature. Any suitable refrigerating medium may be provided in the refrigerating compartment of the cold storage plant and where I refer to ice hereinafter I mean to include any refrigerating medium.

I have discovered that if the cold air circulation from the ice chamber be diverted to the walls surrounding the cold storage chamber and caused to flow downwardly there- 25 through in a substantially continuous sheet about the chamber before entering it I am enabled to utilize this layer of cold air to effectively maintain a low temperature in the cold storage chamber.

As a further development of this idea, I have found that if the cold storage chamber walls be provided with ducts or air passages so that the downward flowing layer of cold air from the ice chamber is split at the 30 bottom of the wall and a part thereof diverted outwardly, I obtain a rising insulating outer layer of cold air which returns through the side walls to the top of the ice chamber and carries with it practically all 35 heat that is radiated through the outer walls and thus diverts it from the storage chamber. The condensation of moisture is reduced to a minimum in the storage chamber which I am able to keep very dry as compared with the present ice chilled cold storage plants. So long as there is sufficient ice in the ice chamber to maintain this outside cold air circulation I can prevent the radiation of 40 heat into the cold storage chamber and maintain its temperature substantially constant.

A further important feature of my invention relates to the manner of construction of the cold storage plant. I have found that building tiles are peculiarly adapted for the 45 formation of the walls with the arrange-

ments of air passages desired and to this end these tiles are used and so laid that they form the necessary inner, intermediate and outer passages for the circulating sheets of air. Moreover the openings in these tiles 60 being in vertical alinement can be filled in with concrete opposite the points where the overhead I-beams or roof supports will rest, thus affording concrete pillars built into the walls for supporting the overhead load of 65 ice as well as the load of meat suspended in the chamber.

My invention also involves improvements in the arrangement of the inlet and outlet ports for cold air circulation in the cold 70 storage chamber and also in the arrangement of the ducts for returning the warm air from the storage chamber to the ice chamber.

As illustrative of the preferred embodiment of my invention, reference is made to the accompanying drawings, in which:—

Figure 1 shows a vertical transverse section through the cold storage structure.

Fig. 2 is a sectional view taken on the 80 line 2—2 of Fig. 1.

Fig. 3 is a vertical sectional view taken on the longitudinal center through the front end of the box showing the entrance vestibule and the air circulation system therefor.

Fig. 4 is a detail view showing a section of the tile walls in perspective carrying the cement column which supports the transverse I-beams.

Similar reference numerals refer to similar parts throughout the drawings.

In constructing the box the floor is laid with hollow tile 1 forming a cold air space 2 and resting upon a separate layer of cork or like material 3 which in turn rests on the floor or foundation for the whole structure. The side walls of the structure are similarly constructed and the description of one will apply to both.

In Fig. 1 I show a cross-section through a side wall. This is formed by elongated building tiles 4 which are of the well known type embodying the intermediate partitions 6 and 7 which subdivide the tile to form three vertical air spaces 8, 9 and 10. These 105 tiles are set vertically with their respective spaces 10 on the inside of the wall and their spaces 9 on the outside of the wall. The spaces 8 serve to separate the inner and outer rows of spaces 9 and 10. The walls are 110

built up in this manner from the floor or base to the top of the cold storage compartment 11. Tiles 12 continue the wall and the outer spaces 9 upwardly to the top of 5 the ice chamber 13. These tiles 12 however are arranged parallel with instead of at right angles to the wall so that their several vertical air spaces register only with the outer spaces 9 of the tiles forming the 10 side wall of the storage chamber. A layer 14 of cork is applied to the side walls of the structure and held in place by a built in wall of sheeting 15. Hollow tiles 22 laid flatwise form the top of the ice chamber. 15 At intervals I provide transversely disposed I-beams 17 to support the load of ice in the chamber 13 and to support the hangers for the meat in the chamber 11. These I-beams abut against the tiles 12 and are supported 20 upon the inner ends of the upper tiles 4 and the vertical partitions 7 of the tiles. In order however to give these I-beams a very strong support, concrete is poured into the registering spaces 8 and 10 where each I- 25 beam is to rest and I thus form concrete columns 18 in the wall which will take the load off the wall tiles. On the lower flange of the I-beams rest transversely arranged T-bars 19 which serve to support flat tiles 30 16 which form the bottom of the refrigerating chamber and the top of the storage chamber. At several points along the center line of the refrigerating chamber I provide vertical stacks 20 formed by square tile having 35 six air spaces therein, the inner spaces of these tiles being filled with concrete to form vertical columns 21 which serve as center supports for the tiles 22 forming the roof of the refrigerating chamber 13. These 40 stacks rest at their lower ends on the T-bars 19 and their outer air spaces 23 are left open below into the top of the storage chamber 11 and have their sides broken away at the top of the refrigerating chamber to form 45 outlet ports 24. Iron columns 25 resting on suitable bases 26 set below the floor tiling 2 serve to support the I-beams 17 at their centers. The floor 27 of the refrigerating chamber, formed on the tiles 16, stops short 50 of the intermediate air ducts 8 of the side walls and if desired also of the rear end wall of the refrigerating chamber so that the cold air chilled by the blocks of ice will flow from the refrigerating chamber over 55 the edges of its floor and down through the central air ducts 8 to the bottom thereof, where the tile is broken away to form ports 28, 29 and 30, the ports 29 admitting the cold air into the air ducts 10 through which 60 it is forced by the descending columns of cold air in the ducts 8 to rise and enter the cooling chamber 11 at the top through ports 31. The ports 30 open from the ducts 10 65 into the cold air space formed in the floor tile 2 and keep the latter filled with cold

air at all times. The outer ports 29 are smaller than the ports 28 and admit a part of the cold air descending through the ducts 8 into the outer ducts 9 in the tile wall, through which ducts 9 the cold air rises and 70 enters the top of the refrigerating chamber through ports 32 thus forming an outer circulating layer of air which takes up the heat that tends to radiate through the walls and diverts it from the cold storage chamber to the refrigerating chamber. The cold air entering the cold storage chamber through the ports 31 flows downwardly in the direction of the arrows, Fig. 1, and then rises to flow through the return passages 23 80 in the columns 20 into the top of the refrigerating chamber. The ports 29 are designed to permit only the requisite percentage of the descending body of cold air to enter the outside air ducts 9 in the wall to prevent 85 any appreciable radiation of heat to the cold air in the central air ducts 8. This permits me to keep the air entering the inside air ducts 10 at a practically uniform temperature and very dry. It will also result that the volume and rate of flow of the cold air in the outer ducts 9 will be automatically proportioned to the external temperature as the latter controls the amount 90 of heat radiated which in turn controls the draft in the flues 9. In very cold weather the draft in the outer flues is negligible and practically the whole circulation takes place through the storage chamber, whereas in 95 very hot weather practically the whole circulation takes place through the outer ducts 9, there being only sufficient amount of the cold air diverted into the storage chamber to preserve its uniform low temperature. 100

In order to, as far as possible, prevent the 105 admission of warm air to the cold storage chamber when it is necessary to enter it, I provide a vestibule entrance 33 having an outwardly opening outer door 34 and an inwardly opening inner door 35, and from the 110 top of this vestibule I lead an air duct 36 (Fig. 3) to the top of the refrigerating chamber where, like the tile stacks 20, it is provided with an outlet port 24 through which the warm air entering the vestibule is 115 returned to the refrigerating chamber and not permitted to enter the cold storage chamber.

It will be understood that the means for obtaining the circulation of air described are 120 only those which I consider preferable as various other arrangements may be resorted to without departure from the principles underlying my invention.

It will be understood that the refrigerating chamber is provided with some suitable drainage system including a trap to carry off the ice water, and should it develop that there is any tendency under excessive heat conditions for moisture to condense in the 130

outer ducts 9 this water will enter the spaces in the floor tiles 2 and these tiles are suitably broken away as at 37 to establish communication between the several transverse air 5 passages formed in the floor so that all may drain to a common trap 38. Under ordinary operating conditions the provision of the trap 38 is unnecessary.

It will also be understood that when I 10 refer to ice and to ice chamber in the specification and claims, I mean to include any refrigerating means and a suitable chamber for containing it.

Having thus described my invention, what 15 I claim as new and desire to secure by Letters Patent, is:—

1. In combination, an ice chamber, a storage chamber below the ice chamber, ducts leading from the ice chamber downwardly 20 and back upwardly through vertical walls of the storage chamber and opening into the upper portion of the storage chamber, and return air ducts leading from the top of the storage chamber upwardly into the ice 25 chamber.

2. In combination, an ice chamber, a storage chamber below the ice chamber, cold air ducts leading from the ice chamber downwardly and back upwardly through opposite 30 site side walls of the storage chamber and opening into the upper portion of the storage chamber, and air return ducts spaced substantially midway between said side walls and leading upwardly from the roof of the 35 storage chamber to the upper portion of the ice chamber.

3. In combination, an ice chamber, a storage chamber below the ice chamber, a series of cold air ducts extending the length of the 40 opposite side walls of said chambers leading from the bottom portion of the ice chamber downwardly and back upwardly through said side walls of the storage chamber and opening at opposite points into the upper 45 portion of the latter, and a plurality of upright warm air return ducts disposed midway between said opposite side walls of said storage chamber and connecting the upper portions of the ice and storage chambers.

50 4. A cold storage structure comprising a top ice chamber and a bottom storage chamber, the storage chamber's marginal walls being formed by vertical conduits which conduct cold air from the ice chamber to the 55 bottom of the said walls and back up to the upper portion of the storage chamber and open thereinto, air return ducts from the storage to the ice chamber, and a hollow bottom for the storage chamber having communication with all said passages and adapted to be charged with cold air thereby.

5. In a refrigerating apparatus, a cold storage chamber, an overhead ice chamber, means to conduct cold air from the ice 60 chamber to the base of walls of the storage

chamber, two sets of conduits to split said cold air circulation at the base of said walls and return part of it through one set directly to the ice chamber and part of it through said walls into the upper part of the storage 70 chamber, and warm air return ducts opening through the storage chamber roof and terminating in the top of the ice chamber.

6. In a refrigerating apparatus, a cold storage chamber, an overhead ice chamber, 75 conduits to conduct cold air from the ice chamber to the base of walls of the storage chamber, ducts to return to the ice chamber part of said cold air through the storage chamber walls in the form of a substantially 80 continuous insulating sheet disposed on the outside of said conduits, and other ducts to return the rest of the cold air to the upper part of the storage chamber and disposed on the inside of said conduits, and top draft 85 flues to return the warm air from the middle portion of the storage chamber's top to the ice chamber.

7. In combination, a cold storage compartment, an ice compartment above the storage 90 chamber, walls of the storage compartment being formed by series of vertical air ducts connected to the said compartments and to each other to cause the cold air from the ice compartment to flow downwardly and back 95 upwardly through walls of the storage compartment before entering the storage compartment, and vertical flues to provide a return circulation of air from the storage to the ice compartment which pass upwardly 100 through the ice compartment at an intermediate point and open near its top.

8. In a cold storage plant, a storage chamber, an overhead ice chamber, three series of air ducts extending downwardly through 105 the walls of the storage chamber, the ducts of the several series being in communication at their lower ends, the intermediate ducts leading from the ice chamber in position to conduct therefrom a circulation of cold air 110 and deliver it to the bottoms of the ducts of the other two series, the ducts of the inner series opening into the storage chamber, the ducts of the outer series opening into the upper portion of the ice chamber, and return air circulation ducts leading from the storage chamber to the ice chamber.

9. In a cold storage plant, a storage chamber, an overhead ice chamber, three series of vertical air ducts extending downwardly 120 through walls of the storage chamber, the ducts of the several series being in communication at their lower ends, the intermediate ducts leading from the ice chamber in position to conduct therefrom a circulation of cold air and deliver it to the bottoms of the ducts of the other two series, the ducts of the outer series being juxtaposed to pass a substantially continuous sheet of air upwardly therethrough to the ice chamber, the ducts 125 130

of the inner series opening into the storage chamber, and return air circulation ducts leading from the storage chamber to the ice chamber.

- 5 10. In a cold storage plant, a storage chamber, an overhead ice chamber, three series of vertical air ducts extending downwardly through walls of the storage chamber, the ducts of the several series being in communication at their lower ends, the intermediate ducts leading from the ice chamber in position to conduct therefrom a circulation of cold air and deliver it to the bottoms of the ducts of the other two series, the ducts of the 10 inner series opening into the top of the storage chamber through opposite side walls thereof, and return air circulation flues leading from the storage chamber to the ice chamber and spaced equi-distantly from said 15 side ducts, the ducts of each series being juxtaposed so as to pass vertically there-through a substantially continuous sheet of air.
11. A cold storage plant comprising a storage chamber, an overhead ice chamber, and cellular walls for said chambers, the cells being arranged to form inner, intermediate and outer series of air ducts in walls of the storage chamber, the intermediate series only 20 having communication with the lower portion of the ice chamber, the inner series having communication with the upper portion of the storage chamber, the outer series having communication with the upper portion 25 of the ice chamber, said walls having ports to deliver the cold air from the bottom of the intermediate cells to the bottoms of the 30 35

inner and outer cells, and return air ducts leading from the storage chamber to the ice chamber.

12. A cold storage plant having a storage chamber with cellular bottom and side walls, an overhead ice chamber with cellular side walls, means to cause a circulation of cold air to pass from the ice chamber downwardly through the walls and into the bottom of the storage chamber and to return part of said circulation to the storage chamber and part to the ice chamber, and return air ducts leading from the storage chamber 40 45 50 to the ice chamber.

13. In a cold storage plant, a storage chamber having cellular side walls formed of hollow tiles which provide therein three series of air vertical passages, the passages of each 55 series extending the length of the walls, hollow tiles forming the side walls of the ice chamber which have communication with the outer series of air passages in the storage chamber wall, the passages of the said several series being in communication at the bottom of the storage chamber walls, the intermediate and outer series of passages having communication at their upper ends at different levels with the ice chamber and 60 65 the inner series having communication with the storage chamber, and air return ducts leading from the storage chamber to the ice chamber.

In testimony whereof I affix my signature. 70

ANDREW C. LEGG.
